UNITED STATES PATENT OFFICE.

IRA LAVENDER, OF WEBSTER CITY, IOWA, ASSIGNOR OF ONE-HALF TO DOCTOR ROY DYSART, OF WEBSTER CITY, IOWA.

CARBURETING DEVICE.

1,048,083.

Specification of Letters Patent.

Patented Dec. 24, 1912.

Application filed December 3, 1910, Serial No. 595,468. Renewed November 14, 1912. Serial No. 731,433.

To all whom it may concern:

Be it known that I, IRA LAVENDER, a citizen of the United States, and a resident of Webster City, county of Hamilton, and 5 State of Iowa, have invented certain new and useful Improvements in Carbureting Devices, of which the following is a specification.

My invention relates to improvements in 10 carbureting devices especially adapted for use in conjunction with internal combustion engines.

The object of my invention is the provision of a carbureting device by means of 15 which a combustible mixture of constant proportions of air and hydro-carbon vapor will be supplied to the engine at all speeds of the latter.

A further object is the provision of a carburetor of the character mentioned which 20 will be of improved construction and efficient in operation.

Other objects will appear hereinafter.

With these objects in view my invention 25 consists in a carbureting device characterized as above mentioned and in certain details of construction and arrangements of parts all as will be hereinafter more fully described and particularly pointed out in 30 the appended claim.

My invention will be more readily understood by reference to the accompanying drawing forming a part of this specification and in which—

35 Figure 1 is a front elevation of a carburetor embodying the preferred form of my invention, Fig. 2 is a central section thereof, and Fig. 3 is a transverse section taken on line $x-x$ of Fig. 2.

40 The preferred form of my invention as illustrated in the drawings comprises a casing or body formed in two parts 1 and 2, said parts being preferably cylindrical in form, the same being rigidly secured together with their open ends registering by 45 means of bolts 3 or other suitable securing device extending through circumferential flanges formed upon the contiguous edges of said parts. Arranged in the part 1 of the 50 casing is an air meter of suitable design, that preferably employed comprising the measuring chamber 4, in which the disk piston 5 is located and operates. The measuring chamber communicates with the air intake port 6 which is open to the outside 55

atmosphere and the exhaust port 7 which is adapted to be connected with or to communicate with the piston chamber of the engine in conjunction with which the carburetor is used. The operation of the air meter is such, as is well known, that the suction caused by the engine when operating will effect the rotation of the disk piston 5 and which rotation will effect the delivery of a measured amount of air from the port 6 to the port 7.

Mounted centrally in the outer head of the casing part 2 is an inwardly projecting stud shaft 8 upon which is rotatably mounted a sleeve 9. Formed at one end of the sleeve 9 is an eccentric 10 and formed at the other extremity thereof a circumferential flange 11. The latter is operatively connected with the disk piston 5 of the air meter by means of an arm 5' which projects in the usual manner from said piston, the outer extremity thereof loosely engaging a perforation 11' formed for the reception thereof in the flange 11; the arrangement being such that upon rotation of the piston 5 caused, as above mentioned, by the engine suction, corresponding rotary movement will be imparted to said flange and hence to the sleeve 9 and eccentric 10. Loosely embracing the eccentric 10 is a rectangular yoke 12, the arrangement being such that rotation of said eccentric effects vertical reciprocation of said rectangular yoke, the eccentric being adapted to effect the elevation of the same and a tension spring 13 effecting the positive return movement thereof. Upwardly projecting from the upper side of the yoke 12 is a piston 14 which is adapted for operation in a cylinder 15 formed in the casing 2. Projecting from the opposite side of said rectangular yoke is an arm 16 which is coaxial with the piston 14, the lower or outer reduced end of said arm 16 slidably engaging a guide screw 17 threaded in the under side of the casing 2. The screw 17 is adapted to be adjusted for engagement with the shoulder 18 formed upon the arm 16 this provision, as will be observed, affording means for the adjustment of the amplitude of movement of the yoke 12 and hence of the piston 14, such adjustment being made possible by reason of the loose engagement of said yoke with the eccentric 10, as clearly illustrated in Fig. 3. With the arrangement disclosed by threading said screw 17

inwardly the stroke of the piston will be shortened and hence the effectiveness correspondingly lessened, outward threading of said screw evidently effecting opposite results.

Formed in the upper end or side of the casing part 2 is a tortuous liquid fluid passage 19 one extremity of said passage terminating in a nipple 20 which affords means 10 of connection with a source of liquid fluid supply, the opposite extremity of said passage communicating by means of a pipe 21 with a nipple 22 which communicates with the measuring chamber of the air meter. 15 The upper extremity of the cylinder 15 is in open communication, as illustrated, with said passage 19, the latter being provided at opposite sides of said cylinder with check valves preferably of the ball type 23 and 24 20 which are adapted normally to seat in valve seats 25 and 26 respectively. Access to said valves for cleaning or repairing may be gained through screw plugs 27. Said valves are so arranged, as will be observed, that 25 upon downward movement of the piston 14 a partial vacuum will be created in the passage 19 between the valves 23 and 24 and which will effect the drawing of liquid fuel past the valve 23, the latter being arranged 30 so as to permit of such passage. Upon said movement of said piston the valve 24 will evidently remain seated. Upon return movement of said piston a portion of the liquid fuel drawn into the portion of the 35 passage 19 intermediate said valves and into the upper end portion of the cylinder 15 will be forced therefrom past the valve 24 into the pipe 21 and thence into the air meter for mixture with the air contained therein for 40 delivery to the combustion chamber of the engine. With this arrangement then it will be seen that reciprocation of the piston 14 such as is caused by operation of the piston 5 of the meter will effect the delivery of the 45 fuel to the latter. Said piston 14 being operatively connected as shown and described with said meter the air delivered by said meter and the liquid fuel fed to said meter for mixture with said air will be constantly 50 in the same proportions; acceleration in the movement of the piston 5 as caused by an increase in speed in the engine will effect a corresponding acceleration in speed of the piston 14 so that an increased supply of air 55 delivered by the meter will effect a corre-

sponding increase in the supply of liquid fuel, the speed of the piston 14 being governed directly by that of the piston 5. By reason of the adjustment afforded by the screws 17 the proportion of liquid fuel to 60 that of air delivered to the engine may be varied in order that a mixture of exactly proper proportions may be formed. With a device then of a construction as set forth a proper mixture may at all times be formed 65 and this proportion maintained at all speeds of the engine.

While I have illustrated and described the preferred form of my carburetor I do not wish to be limited thereto as there might be 70 many changes made in the details of construction and the arrangements of parts described without departing from the spirit of the invention as comprehended within the scope of the appended claim.

Having described my invention what I deem as new and desire to secure by Letters Patent is:—

In a carbureting device, the combination 80 of an air meter comprising a rotatable member adapted to be rotated by the suction created by an internal combustion engine when operating, said rotatable member being adapted when rotated to deliver air from an air intake port in communication with 85 the outside atmosphere to an outlet port adapted to communicate with the combustion chamber of the engine; a rotatable eccentric; an operative connection between said rotatable member of said meter and 90 said eccentric whereby rotation of the former effects corresponding rotation of said eccentric; a rectangular yoke loosely embracing said eccentric; a piston carried by said yoke; a liquid fuel passage leading to said 95 meter, one end of the cylinder of said piston communicating with said passage; and a check valve in said passage at either side of said cylinder, whereby reciprocation of said piston effects the forcing of liquid fuel 100 in said passage toward said meter, substantially as described.

In testimony whereof I have signed my name to this specification in the presence of two subscribing witnesses.

IRA LAVENDER.
